ROLLING BLIND

Jan Sjoerd Zwart, Batavia, Java, Dutch
East IndiesApplication August 11, 1939, Serial No. 289,608
In the Netherlands September 2, 1938

1 Claim. (Cl. 156—16)

My invention relates to a rolling blind or revolving shutter consisting of a number of laths or strips hinged to each other.

It is an object of my invention to provide such 5 a rolling blind for windows which in its closed position prevents sunshine and rain to penetrate through the window, but allows fresh air to pass.

It is known to make a rolling blind of laths 10 which are hinged to each other by means of metal wires wound around the individual laths in the shape of loops, each loop being led through the closed end of the wire loop of a neighbouring lath.

According to my invention the closed end of 15 each such loop is arranged at some distance from the lower edge of the lath around which the loop is wound; it is bent approximately perpendicular to this lath and has such a length that it partly covers the upper edge of the following lower lath. 20 Thus I obtain a rolling blind with the adjacent laths overlapping each other along their horizontal edges, which can easily be rolled up and out and secures perfect protection against sunshine and rain, while clefts are formed between the 25 individual laths for the passage of air for ventilation.

In the drawing affixed to this specification and forming part thereof an embodiment of my invention is illustrated diagrammatically by way of 30 example.

In the drawing

Fig. 1 is a side view, partly in section, of a rolling blind according to the invention, and

Fig. 2 is a perspective view of a part of this 35 rolling blind.

Referring to the drawing, 1 designates the laths or strips of which the rolling blind is composed and which are united and hinged to each other by means of one or several chains the links of 40 which are formed by metal wire loops 2 wound around the laths 1. The closed end 3 of every such loop is bent approximately perpendicular and arranged somewhat distanced from the lower

edge of the lath around which the loop is wound. This bent part of the loop rests on the upper edge of the following lath and has such a length that it partly covers said upper edge.

From each loop the metal wire extends upwardly in two branches which are wound around the lath. The ends form hooks 4 and are put through the bent part of the loop.

Since the bent part of the loop, which rests on the upper edge of the following lath and in this 10 way forms the hinging point of this lath, is arranged at some distance from the lower edge of the lath, the rolling blind when running out presents a gradual arrangement of the laths, the metal wires and in particular the ends of the 15 wires, which are bent forwards and shaped like hooks, giving rise to clefts between each lower and the upper edge of adjacent laths sufficient to let through enough air for the ventilation, while at the same time a complete protection 20 against sunshine and rain is obtained. The new rolling blind can easily be wound up by a very simple lifting mechanism.

The revolving shutter according to this invention may also be applied in the form of a Florentine blind.

I wish it to be understood that I do not desire to be limited to the exact details of construction shown and described for obvious modifications will occur to a person skilled in the art.

I claim:

Rolling blind comprising in combination, a plurality of laths hinged to each other, a metal wire wound around each of said laths in the form of a loop led through the closed end of the loop of an adjacent lath in such manner that the closed end of each loop is bent approximately perpendicular to the lath, around which this loop is wound, and is arranged, in some distance from the lower edge of this lath, so as to partly cover 35 the upper edge of the adjacent lower lath.

JAN SJOERD ZWART.
